(57) **CLAIM**

I claim the ornamental design for shaped tortilla, as shown.

DESCRIPTION

FIG. 1 is a perspective view of a shaped tortilla, according to the present invention;

FIG. 2 is a top plan view of the shaped tortilla of FIG. 1;

FIG. 3 is a bottom plan view of the shaped tortilla of FIG. 1;

FIG. 4 is a right side view of the shaped tortilla of FIG. 1;

FIG. 5 is a left side view of the shaped tortilla of FIG. 1;

FIG. 6 is a front end view of the shaped tortilla of FIG. 1;

FIG. 7 is a rear end view of the shaped tortilla of FIG. 1;

FIG. 8 is a longitudinal section view of the shaped tortilla of FIG. 1; and,

FIG. 9 is a transverse section view of the shaped tortilla of FIG. 1.
